DIGITAL CLOCK

Ellsworth R. Danz, La Salle, and John C. Crenshaw,
Joliet, Ill., assignors to General Time Corporation,
Thomaston, Conn.

Filed Aug. 14, 1974, Ser. No. 497,452

Term of patent 14 years

Int. Cl. D10—01

U.S. Cl. D10—15

FIG. 1.

FIG. 2.

FIG. 3.

FIG. 4.

FIG. 5.

FIG. 6.

FIG. 1 is a front perspective view of a digital clock showing our new design;

FIG. 2 is a front elevational view thereof;

FIG. 3 is a side elevational view taken along line 3—3 of FIG. 2;

FIG. 4 is a plan view thereof;

FIG. 5 is a rear elevational view thereof; and

FIG. 6 is a bottom view thereof.

We claim:

The ornamental design for a digital clock, substantially as shown.
